CLAIM

The ornamental design for a car accessory, as shown and described.

DESCRIPTION

FIG. 1 is a perspective view of a car accessory showing our new design, shown in its position of use;

FIG. 2 is an enlarged top view thereof, it being understood that the bottom is a mirror image thereof;

FIG. 3 is an enlarged front elevation view thereof;

FIG. 4 is an enlarged right side elevation view thereof; and,

FIG. 5 is an enlarged rear view thereof.

The broken line showing of environment is for illustrative purposes only and forms no part of the claimed design.
